(57) **CLAIM**

The ornamental design of a “hand-held cautery device”, as
shown and described.

DESCRIPTION

FIG. 1 is a perspective view of a hand-held cautery device of
our new, original and ornamental design;
FIG. 2 is a top view of the hand-held cautery device of FIG. 1
with the cover member removed for ease of illustration;
FIG. 3 is a bottom view of the hand-held cautery
device thereof;

FIG. 4 is a right side view of the hand-held cautery device
thereof, with the left side being a mirror image thereof;
FIG. 5 is an enlarged front view of the hand-held cautery
device thereof; and,
FIG. 6 is an enlarged back view of the hand-held cautery
device thereof.

The broken lines showing in FIG. 6 are for illustrative pur-
poses only and form no part of the claimed design.
